CLAIM

The ornamental design for a game controller extended thumbstick cover, as shown and described.

DESCRIPTION

FIG. 1 is a front, top, and right perspective view of a game controller extended thumbstick cover, comprising two components, showing my new design.

FIG. 2 is a rear, bottom, and left perspective view thereof.

FIG. 3 is a top plan view thereof.

FIG. 4 is a bottom plan view thereof.

FIG. 5 is a right side view thereof; a left side view being a mirror image thereof.

FIG. 6 is an exploded perspective view thereof, showing first and second components of the assembly.

FIG. 7 is a front, top, and right perspective view of the first component of the game controller extended thumbstick cover.

FIG. 8 is a rear, bottom, and left perspective view of the first component thereof.

FIG. 9 is a top plan view of the first component thereof.

FIG. 10 is a bottom plan view of the first component thereof; and,

FIG. 11 is a right side view of the first component thereof; a left side view being a mirror image thereof.

The components of the game controller extended thumbstick cover are depicted separately in the exploded perspective view of FIG. 6 for clarity of illustration, and the bracket embracing the separate parts forms no part of the claimed design.
